UNITED STATES PATENT OFFICE.

JACOB CODOS AND BENJAMIN MAY, OF NEW YORK, N. Y.

DOOR-LOCK.

1,258,746.

Specification of Letters Patent. Patented Mar. 12, 1918.

Application filed August 15, 1917. Serial No. 186,268.

To all whom it may concern:

Be it known that we, JACOB CODOS and BENJAMIN MAY, residents of the city of New York, county and State of New York, 5 have invented certain new and useful Improvements in Door-Locks, of which the following is a specification.

Our invention relates to certain new and useful improvements in door locks, the object of this invention being to provide a safe 10 and simple door lock.

To attain this object we employ the devices shown in the accompanying drawings, in which—

15 Figure 1 is a view showing the mechanism with the cover plate removed.

Fig. 2 is a detailed view of one of the sliding bolts.

Fig. 3 is a section on line A—A of Fig. 1.

20 The device consists of a casing 1, with a pair of guide ways 2 and 3, on which are slidably mounted the sliding bolts 4 and 5. These bolts are slidable to and from each other. The detail of one of these is shown 25 in Fig. 2. At about the center of each of these bolts is a pin or projection 6 and 7. This projection extends through the cam shaped slots 8 and 9 in the bolt operating slide 10. This bolt operating slide operates 30 back and forth in a direction at right angles to that of bolts 4 and 5, and is guided on the lug 11. At one end of the bolt operating slide is the slot 12 wherein is slidably mounted the detaining dog 13. This dog 13 is 35 held downward by means of a spring 14.

This device is operated by means of a key which is inserted through the keyhole 14 and

rotates in the direction of arrow 15 until it comes in contact with the lower end of dog 13. The continued rotation of the key 40 causes the dog 13 to be raised until it is clear of the lug 15, then the key comes in contact with the slot side 12 and moves the bolt slide in the direction of arrow 16 until the pins 6 and 7 are engaged by the angular 45 or cam shaped portions of the slots 8 and 9, and the bolts 4 and 5 are drawn apart or away from each other.

The keeper for the sliding bolts consists of a body member 17 with the lug 18 thereon, 50 this lug is provided with an opening 21 wherein the projections 19 and 20 enter when the lock is in its closed position.

In Fig. 3 the casing is shown mounted on a swinging door 22 and the keeper on a door- 55 post 23.

What we claim is:—

A door lock comprising a casing containing a pair of sliding bolts arranged to slide toward and from each other, a keeper comprising a body member with a lug having an opening therein for engaging the sliding bolts, a bolt operating slide arranged to slide at right angles to the sliding direction of the bolts and having a pair of cam shaped slots 60 therein for operating the bolts and a detaining dog operatively mounted on the said bolt operating slide. 65

JACOB CODOS.
BENJAMIN MAY.
